UNITED STATES PATENT OFFICE

2,479,898

BOWLING BALL CLEANER OR POLISHER

Victor Beaudette, Old Orchard Beach, Maine;
 Henry Beaudette, administrator of said Victor
 Beaudette, deceased, assignor to Henry Beau-
 dette, Old Orchard Beach, Maine, and Edward
 Beaudette, Hartford, Vt.

Application February 19, 1947, Serial No. 729,509

3 Claims. (Cl. 51—111)

1

This invention relates to a bowling ball cleaner and provides means whereby the ball is placed in a position to be engaged by cupped members, after which the cupped members are rotated and the ball cleaned or polished during such operation.

The main object of the invention is to provide a ball cleaner comprising oppositely disposed cup-shaped members which are filled with steel wool or the like, the said cup-shaped members being adapted to be moved into engagement with the bowling ball, rotated, separated, whereby the ball is released after having been cleaned.

Another object of the invention is to provide a simple electrically operated machine having means whereby only one of the cup-shaped polishers is moved into engagement with the ball, the other cupped member being stationary.

The invention is illustrated in the accompanying drawings, in which:

Figure 1 is a side elevational view;

Figure 2 is a top plan view of the machine;

Figure 3 is a view similar to Figure 1 but showing the upper portion of the machine in central longitudinal vertical section—see line 3—3 of Figure 1;

Figure 4 is a horizontal sectional view taken on line 4—4 of Figure 3;

Figure 5 is an end elevational view taken from the "left" as viewed in Figure 1;

Figure 6 is a vertical cross sectional view taken on line 6—6 of Figure 1;

Figure 7 is a vertical sectional view taken on line 7—7 of Figure 3; and

Figure 8 is a fragmentary horizontal sectional view taken on line 8—8 of Figure 6.

Referring specifically to the machine, the same comprises leg members 6, mounted between which is a shelf 7, carrying an electric motor 8. To the upper portion of the leg 6 is attached guides 9. Said guides 9 provide a support for the carrier base 10a of a rotatable cup-shaped member 10. Base 10a has horizontal groove-providing flanges 10b engaging the lateral flanges 13 of guides 9, and clamp nuts 10c secure base 10a in fixed position. Guides 9 also support a movable cup-shaped member 11, this member being mounted on a carriage 12, said carriage having horizontal side grooves engaging the aforementioned oppositely flanged portions 13 of the members 9.

The cup members are provided at their rear ends with spindles 14 mounted in bushings 15 and 16. Inasmuch as both cup members are alike, only one will be described.

The spindle of the cup members have attached

2

thereto a pulley 17, said pulley being driven by a belt 18 from a pulley 19 which is mounted on a drive shaft 20, said drive shaft supporting another pulley 21, which is driven by a belt 22 from a sheave 23 on the driven end of the motor. The shaft 20 is provided with a gear 24 meshing with a gear 25, said gear 25 being rigidly attached to a shaft 26 having a pulley 27 mounted thereon, as by a spline 28, or the like. Pulley 27 drives a belt 29 engaged in the pulley 30, which pulley is rigidly mounted on the spindle of the movable cup-member 11. The members 9 also support a rubber cushion 31, this cushion being adapted to support a bowling ball which has been placed in position on the supporting cushion to be engaged between the cupped members when the member 11 is moved toward the stationary cup 10. The underframe comprises a link 32 which is attached as at 33 to the base 12 of the movable cup member 11. This link has pivoted thereto at 34, a lever 35, said lever being pivoted as at 36 to one of the frame members 9. The lever 35 has an extension or handle member 35a extending through an opening 38 in the side of the member 9, whereby the same may be grasped to move the frame 12 toward and away from the stationary cup member 10.

Shown at 39 is a lever for operating a lock device 40 of any well known construction, such as 30 a lag screw whose end engages the subjacent frame flange 13 (see Fig. 6).

Thus, it will be seen that when it is desired to polish or clean a bowling ball, it is only necessary to have the cups separated enough to accommodate the ball and allow the same to rest on the member 31, whereupon the lever 35 is moved as by the handle 35a to bring the respective cups into close engagement, thereby holding the ball in a position to be cleaned. After this has been done, the motor is started and through the belting, pulley and shaft arrangement, the cups are rotated there-between at high speed, and it is only a matter of minutes before the bowling ball is well cleaned and ready for use again. The motor is stopped, the lever 35 actuated by the handle 35a to retract the cup 11 whereupon the ball can be readily removed and the next ball placed in the machine.

The invention is not limited to the exact construction shown but is capable of variation within the scope of the following claims.

Having thus described my invention, what I claim is:

1. A machine for polishing bowling balls or the like, comprising a frame, parallel guide mem-

bers having flanged portions supported on said frame, oppositely disposed cup-shaped members comprising carriages having longitudinal side recesses mounted on and engaging the flanged portions of the guide rails, a resilient ball support mounted on the guide rails and substantially between the cup-shaped member, and a lever means for moving one of the cup-shaped members longitudinally with respect to the other cup-shaped member to engage a ball which has been placed on the ball support between the cup-shaped members.

2. A bowling ball cleaning machine comprising a frame structure, flanged guide rails mounted on said frame structure and supporting oppositely disposed ball engaging members, carriages for the respective ball engaging members having horizontal side grooves engaging the said guides, the carriages having bearings for supporting the spindles of the ball engaging members, an electric motor, a drive shaft, and belt and pulley means between the drive shaft and the respective spindles of the ball engaging members, whereby the ball engaging members can be rotated to polish a ball engaged between said members.

3. In a ball cleaning and polishing machine, the combination comprising a frame structure, a pair of flanged guide rails mounted on said frame structure, a pair of carriages provided at their bases with side grooves engaging the flanges of the guide rails, said carriages consisting of spaced

bushings and a spindle mounted in said bushings and supporting a cup-shaped ball engaging member, a recessed resilient ball supporting member, spaced below and between the respective ball engaging members, a pivoted hand lever mounted on and extending through one side of the guide rails and engaging a link connected to one of the carriages to move the carriage and its ball engaging member into cooperation with the other ball engaging member, an electric motor, a drive shaft, and belt and pulley means between the drive shaft and the respective spindles of the ball engaging members.

VICTOR BEAUDETTE.
